Felix N. Hollander, Coeur d'Alene, Idaho

Application May 27, 1952, Serial No. 19,907

Term of patent 7 years

(Cl. D48—20)

To all whom it may concern:

Be it known that I, Felix N. Hollander, a citizen of the United States, residing at Coeur d'Alene, in the county of Kootenai and State of Idaho, have invented a new, original, and ornamental Design for a Combined Lamp and Stand, of which the following is a specification, reference being had to the accompanying drawing, forming part thereof.

Figure 1 is a perspective view of a combined lamp and stand, showing my new design;

Figure 2 is an elevational view thereof;

Figure 3 is a horizontal sectional view on the line 3—3 of Figure 2 looking in the direction of the arrows; and

Figure 4 is a horizontal sectional view on the

line 4—4 of Figure 2 looking in the direction of the arrows.

I claim:

The ornamental design for a combined lamp and stand, as shown.

FELIX N. HOLLANDER.
